UNITED STATES PATENT OFFICE

WILLIAM P. DAY, OF CLEVELAND HEIGHTS, OHIO, ASSIGNOR TO THE INTERNATIONAL STEEL TIE COMPANY, OF CLEVELAND, OHIO, A CORPORATION OF DELAWARE

ROADBED CONSTRUCTION FOR STREET RAILWAYS AND METHOD OF CONSTRUCTING THE SAME

Application filed September 15, 1928. Serial No. 306,224.

This invention relates to a road bed for street or boulevard railways and to a method of forming the same.

The main object of the invention is to provide a road bed structure and method of forming the same which will permit the rails to be removed for replacement or repair without disturbing any portion of the track except that immediately adjacent the rails.

10 Another object of the invention is to provide a road bed construction in which the rails and rail supporting structure are rigidly and firmly held in place and in which creeping of the rail is reduced to a minimum.

15 Another object of the invention is to provide a road bed construction of the character set forth in which the rail supporting members and the pavement between and adjacent the rails are interlocked with each other in such a manner that separation of the rail from the paving and concrete base is practically prevented.

Another object of the invention is to provide a road bed construction of the character described which will maintain the track in the proper alignment and in which that portion of the road surface adjacent the rails will not become broken as a result of heavy loads passing over the rails.

20 A further object of the invention is to provide a road bed construction in which the rail clips may be tightened without disturbing any portion of the road surface except that immediately adjacent the rail clip to be tightened.

25 A further object of the invention is to provide a road bed construction of the character set forth employing a plurality of stringers or baffle plates extending along each rail in spaced parallel relation thereto and which maintains a line of cleavage between that portion of the road bed immediately adjacent the rails and the remaining portion of the road bed.

30 A further object of the invention is to provide a method of forming a road bed construction providing a road surface having a pair of parallel trenches in which are firmly and rigidly secured a plurality of rail supporting members, then detachably securing

the rails to said rail supporting members and then filling the trenches with a readily removable road forming material whereby the rails may be removed for replacement or repair without disturbing the remaining portion of the road surface.

Still another object of the invention is to provide a road construction and method of forming the same which will insure and provide a very rigid type of track foundation which can be laid with a minimum cost and in which lower rails can be used on account of the girder strength of the tie structure.

Further and more limited objects of the invention will appear as the description proceeds and by reference to the accompanying drawings in which Fig. 1 is a fragmentary top plan view of a portion of a road bed constructed in accordance with my invention; Fig. 2 is a vertical sectional view on the line 2—2 of Fig. 1; Fig. 3 is a fragmentary top plan view of the road construction with the rail supporting member in place but before the rails have been secured in place, and Fig. 4 is a vertical sectional view on the line 4—4 of Fig. 3.

Referring now to the drawings, the reference character 1 designates the lower pavement or foundation of any well known construction and 2 the upper pavement having a smooth surface. The surface of the foundation is preferably coated with a waterproofing material so as to prevent water from seeping down into the foundation.

In order to provide a suitable support for the rails I provide cross ties of the twin type which are preferably made of steel. The cross ties each embody a pair of rail supporting plates 3 and 4 which are connected by transverse tie plates or channel irons 5 and 6. The supporting plates 3 and 4 are provided at each end with oppositely disposed pairs of T-shaped openings 7 and 8, respectively, the purpose of which will hereinafter appear. The cross ties are laid upon and rest on the foundation 1, the foundation having been first coated with a waterproofing material. The rails are then placed on the rail supporting plates and are detachably secured thereto by rail clamps 9, bolts 10, 11,

and nuts 11. The heads of the bolts 10 are substantially rectangular in shape and are of such a size that the bolts, when in one position, may be inserted through the T-shaped openings and then turned at right angles so as to engage beneath the edges of the openings. The details of the cross ties and the rail clips are disclosed and claimed in my copending application Serial No. 303, 501, filed September 1, 1928.

I then secure along each rail at a distance therefrom a pair of baffle plates or trench forming members 12 and 13 which are preferably disposed at an angle to each other and converge downwardly. The lower edges of the plates 12 and 13 are preferably spot welded to the rail supporting plates 3 and 4. The upper pavement 2 is then laid leaving a trench or channel along each rail, as shown most clearly in Fig. 4. The trenches or channels are then filled with a readily removable road forming material up to the level shown in Fig. 2. The material filling the trenches is preferably of a different nature than that forming the remaining portion of the road surface. It is, of course, understood that the trenches are filled by pouring the concrete or other material thereinto while the same is in a plastic condition.

If the rail becomes loosened during the life of the track, the clip can be tightened without removing or disturbing any portion of the road bed except that immediately adjacent the loosened clip. The longitudinally extending plates in the pavement keep cool and tend to prevent movement of the rails due to temperature changes and serve to relieve or prevent strain on the rail joints. These plates also tend to prevent the ties from "walking" back and forth during the building period.

When it is desired to remove the rail for replacement or repair, the material filling the trenches is removed and the rail clamps disconnected. The rail may then be removed leaving the bolts 10 in place, as shown most clearly in Fig. 4.

Various changes may be made in the details of construction and in the method of forming the road bed without departing from the spirit of my invention and it is understood that my invention is limited only in accordance with the scope of the appended claims. It should also be understood that my invention is not limited to any particular type of road surface or foundation and that in some cases it may not be advisable to secure the baffle plates to the rail supporting plates. In some cases also it may be desirable to omit the plates, it merely being necessary to maintain a line of cleavage or demarcation along the removable portion of the road bed.

It will now be clear that I have provided 65 a road bed construction and method of form-

ing the same which will accomplish the objects of the invention as hereinbefore stated.

Having thus described my invention, what I claim is:

1. A road bed for street railways comprising a road surface having a pair of spaced parallel trenches formed therein, bearing plates disposed within said trenches, tie members connecting said bearing plates and extending transversely of the track, a pair of rails supported by said bearing plates, rail clamps securing said rails to said bearing plates, a pair of upwardly diverging baffle plates disposed within each of said trenches and having their lower edges spaced apart a distance greater than the width of the base of the rail and connected with said bearing plates and a removable filler substantially filling said trenches, said baffle plates forming a clear line of demarcation or cleavage between the road bed proper and the rail supporting portion thereof, the rails being removable independent of the supporting structure therefor and without disturbing any portion of the road surface except that within the trenches. 70 75 80 85

2. A road bed for street railways comprising a road surface having a pair of spaced parallel trenches formed therein, the width of said trenches being greater than the width of the base of a rail, bearing plates disposed within said trenches, tie members connecting said bearing plates and extending transversely of the track, a pair of rails supported by said bearing plates, rail clamps securing said rails to said bearing plates, a pair of downwardly converging baffle plates disposed within each of said trenches and having their lower edges connected with said bearing plates and a removable filler substantially filling said trenches, said baffle plates forming a clear line of demarcation or cleavage between the road bed proper and the rail supporting portion thereof, whereby the rails may be removed independent of the supporting structure therefor and without disturbing said plates. 90 95 100 105 110 115

3. A road bed for street or boulevard railways comprising a hard surface road having a pair of spaced parallel trenches formed therein, bearing plates arranged within said trenches, tie members connecting said bearing plates and extending transversely of the track, a pair of rails supported by said bearing plates and rigidly connected therewith, a pair of upwardly diverging baffle plates arranged within each of said trenches and spaced apart a distance at least as great as the width of the base of the rails and a filler substantially filling each of said trenches, the upper surface of the rails being at substantially the same level as the surface of the road, the rails being removable from said trenches independent of the supporting structure therefor and without disturbing said plates. 120 125 130

4. A road bed for street or boulevard railways comprising a hard surface road having a pair of spaced parallel trenches formed therein, bearing plates arranged within said trenches, tie members connecting said bearing plates and extending transversely of the track, a pair of rails supported by said bearing plates and rigidly connected therewith, a pair of downwardly converging baffle plates arranged within each of said trenches respectively and a filler substantially filling each of said trenches, said baffle plates being spaced apart a distance greater than the width of the base of the rail, the upper surface of the rails being at substantially the same level as the surface of the road, the rails being removable from said trenches independent of the supporting structure therefor and without disturbing said plates. 70
5. A rail supporting structure of the character described comprising a road bed, a plurality of ties supported by said road bed, a pair of rails resting on said ties, oppositely disposed pairs of downwardly converging baffle plates disposed along each rail in spaced relation thereto and providing a channel extending along each rail, the lower edges of said baffle plates being spaced apart a distance greater than the width of the base of the rail rigidly connected with said ties respectively, a filler substantially filling each of said channels, the remaining space between and along said rails being filled with concrete substantially up to the level of the top of the rails, the rails being removable without disturbing any portion of the road bed except said channels and without disturbing said baffle plates. 80
6. A rail supporting structure of the character described comprising a base, a plurality of ties supported by said base, a pair of rails resting on said ties respectively, oppositely disposed pairs of downwardly converging baffle plates disposed along each rail in spaced relation thereto and providing a channel extending along each rail, a filler substantially filling each of said channels, the remaining space between and along said rails being filled with road forming material substantially up to the level of the top of the rails, the rails being removable without disturbing any portion of the road bed except said channels. 90
7. A rail supporting structure comprising a base, bearing plates supported on said base at intervals and adapted to support a pair of rails, transverse tie members connecting said bearing plates and extending transversely between the rails, a pair of downwardly converging baffle plates arranged along each rail in spaced relation thereto and providing a channel along each rail, a layer of concrete filling the space between and adjacent the track except said channels and a material substantially filling said channels, said baffle plates being rigidly connected with said bearing plates at their lower edges, the rails being removable without disturbing the supporting structure therefor and without disturbing said baffle plates. 100
8. In a road bed construction for street or boulevard railways, the combination of transversely disposed rail supporting members adapted to support a pair of spaced parallel rails, and longitudinally extending trench forming means extending along each of said rail supporting members, said trench forming members being spaced apart a distance greater than the base of the rail and diverging upwardly so that the rail may be removed and replaced without disturbing the road surface between or adjacent said trenches. 110
9. In a road bed for street railways, the combination of oppositely disposed rail supporting members adapted to support a pair of rails thereon in spaced relation, transverse tie members connecting said rail supporting members and longitudinally extending downwardly converging trench forming plates extending along each of said rails whereby said rails may be removed without disturbing any portion of the road surface except that within said trenches. 120
10. In a road bed construction for street railways, the combination of a plurality of transversely disposed rail supporting members adapted to support a pair of rails thereon in spaced relation, of a pair of longitudinally extending downwardly converging trench forming plates extending along each of said rails in spaced relation thereto. 130
11. In a road bed construction for street railways, the combination of a plurality of transversely disposed rail supporting members adapted to support a pair of rails thereon in spaced relation, of a pair of longitudinally extending downwardly converging trench forming plates extending along each of said rails in spaced relation thereto, said trench forming plates having their lower edges rigidly connected to said rail supporting members. 140
12. In a road bed construction for street railways, the combination of a foundation, of transversely disposed rail supporting members resting on said foundation and adapted to support a pair of rails thereon in spaced relation, means detachably connecting said rails to said rail supporting members, a pair of downwardly converging longitudinally extending trench forming plates extending along each rail and having their lower edges rigidly connected to said rail supporting members, a filler of readily removable material filling said trenches and a street forming material filling the remaining space between and along the track, the rails being readily removable from said trenches with- 150

out disturbing the remaining portion of the road bed.

13. A road bed construction for street or boulevard railways comprising a road surface having a pair of spaced parallel trenches 5 therein, the opposite side walls of each of said trenches converging downwardly, bearing plates disposed within each of said trenches, rails supported by said bearing plates and detachably secured thereto, a pair of oppositely disposed upwardly diverging baffle plates disposed within each of said trenches and having their lower edges connected with said bearing plates and a readily removable initially plastic filler filling said trenches, said 15 baffle plates forming a line of cleavage between the road bed proper and the rail supporting portion thereof whereby the rails may be readily removed without disturbing 20 any portion of the road surface except that within said trenches.

14. A rail supporting structure of the character described comprising a road bed having a pair of spaced parallel trenches 25 therein, bearing plates arranged in said trenches and supported by said road bed, transverse tie members connecting said bearing plates, rails detachably secured to said bearing plates, a pair of downwardly converging baffle plates arranged within each of 30 said trenches and spaced from each other a distance greater than the width of the base of said rails, initially plastic filler material filling said trenches, means rigidly connecting said baffle plates and bearing plates, the 35 rails being removable independent of the supporting structure therefor and without disturbing said baffle plates.

15. The method of forming a road bed for 40 street or boulevard railways which consists in providing a road surface having a pair of spaced parallel trenches therein of substantially the same depth as the height of a standard rail and of greater width than the base 45 of a standard rail, the side walls of said trenches converging downwardly arranging within each of said trenches a plurality of rail supporting members, securing the rails to said rail supporting members respectively, 50 filling said trenches with an initially plastic readily removable road forming material and allowing said material to harden and set, and maintaining a line of cleavage or demarcation between the said trenches and the remaining portion of the road surface whereby 55 the rails may be readily removed without disturbing any portion of the road except that within said trenches.

16. The method of forming a road bed for 60 street or boulevard railways which consists in providing a road surface having a pair of spaced parallel trenches of substantially the depth of a standard rail and of greater width than the base of a standard rail, detachably 65 securing a rail within each of said trenches,

arranging within each of said trenches a pair of downwardly converging baffle plates the bottom edges of which are spaced from said rails, filling the trenches with an initially plastic road forming material and allowing the material to harden and set whereby the rails may be removed without disturbing any portion of the road surface except that within the trenches.

In testimony whereof, I hereunto affix my 75 signature.

WILLIAM P. DAY.
